UNITED STATES PATENT OFFICE.

AXEL W. HAWKINSON, OF WASHINGTON, PENNSYLVANIA, ASSIGNOR TO SIDWAY-
TOPLIFF COMPANY, OF WASHINGTON, PENNSYLVANIA.

TOY AUTOMOBILE.

Application filed November 25, 1925. Serial No. 71,441.

To all whom it may concern:

Be it known that I, AXEL W. HAWKINSON, a citizen of the United States, and resident of Washington, in the county of Washington and State of Pennsylvania, have invented certain new and useful Improvements in Toy Automobiles; and I do hereby declare the following to be a full, clear, and exact description of the invention, such as will 10 enable others skilled in the art to which it appertains to make and use the same.

This invention relates to improvements in children's vehicles, such as toy automobiles, for example.

15 One object of the invention is to so construct propelling mechanism for the vehicle of the type specified that the same can be started from any position with either or both of the pedals and with any length of 20 stroke.

A further object is to so construct manually operable propelling mechanism for a toy automobile or the like, that dead centers shall be avoided.

25 With these and other objects in view, the invention consists in certain novel features of construction and combinations of parts as hereinafter set forth and pointed out in the claims.

30 In the accompanying drawings,

Figure 1 is a longitudinal sectional view showing an embodiment of my invention.

Figure 2 is a rear end view partly in section.

35 Figure 3 is an enlarged view showing portions of the propelling or driving mechanism, and

Figures 4, 5 and 6 are views showing details.

40 In the drawings, the frame or chassis is represented at 1, and is supported at its forward end on an axle 2 and front wheels 3, through the medium of suitable springs 4 or in any other desired manner.

45 Rearwardly and downwardly extending springs 5 are secured at their forward ends to the side members of the frame 1, and to the rear ends of said springs, brackets 6 are secured. To these brackets, hangers 7 are

50 secured and support fixed sleeves or bushings 8 through which the rear axle 9 is adapted to pass and in which said axle is rotatable, said axle having secured to its respective ends, the rear wheels 10 of the car.

55 The arms 11 of a transversely disposed

yoke 12 are rigidly secured at their outer ends to the brackets 6, preferably by the same rivets which secure the hangers 7 to the brackets 6, as illustrated in Figure 4.

Ratchet wheels 13—13 are secured to the central portion of the rear axle 9 and may be separated from each other by means of disks or washers 14. Plates 15 are mounted loosely upon the axle 9 and adjacent to the respective ratchet wheels 13. A dog or pawl 65 16 is pivotally attached to each plate 15 and the teeth of these dogs or pawls are forced into cooperative relation to the ratchet wheels respectively, by means of springs 17, one end of each of which is attached to one 70 of the plates 15 and the other end to the adjacent dog or pawl 16. The dogs or pawls 16 are pivotally supported near their toothed lower ends and extend upwardly an appreciable distance to provide tail portions 75 18, for a purpose hereinafter explained.

The plates 15 are provided, each with a plurality of lugs 19 which may be bent out from the metal of said plates and these lugs form in effect sprocket teeth, with 80 which a plurality of connected links 20, forming in effect a sprocket chain, cooperate. One end of each chain or connected links, is pivotally attached as at 21 with the lower end of the adjacent plate 15. The link 85 20 at the other end of each chain or series of connected links has pivotally connected thereto the rear end of a rod or pitman 22. The forward ends of the pitmen 22 are connected with pedals 23, the latter being suspended from the frame by means of pivoted links or rods 24. It is apparent that when either or both of the pedals 23 are depressed, one or both of the ratchet plates 15 will be turned by cooperation therewith of the 90 connected links 20 and that the turning of these plates will cause the dogs carried thereby to turn the ratchet wheels and hence the rear axle, thereby propelling the car forwardly. Springs 25 are provided for returning the plates 15 and the dogs to their normal positions when pressure on the pedals is relieved. These springs are mounted on sleeves 26 on the axle 9 and each of these sleeves may be provided at its outer 95 end with a collar 27 secured to the axle 9 by means of a set screw 28. The inner ends of these springs 25 are connected with the plates 15 and their outer ends are attached 100 as at 29 to the yoke arms 11.

- The yoke 11 has secured thereto, arms 30 which provide bearings for a crank-shaft 31. One end of this crank-shaft is provided with an arm 32, with which one end of a pitman 33 is connected, the other end of said pitman being connected with the lower arm of a hand lever 34 pivotally connected with one side bar of the frame or chassis 1 and this hand lever 34 carries a detent 35 for cooperation with a toothed segment 36 also secured to the same frame side bar. When the lever 34 is moved rearwardly, motion will be imparted to the crank-shaft 31 so as to cause its crank arm 31^a to engage the tail portions 18 of the dogs or pawls 16 and move the latter out of cooperative relation to the ratchet wheels 13. The car may now be permitted to coast freely or it may be backed if so desired.
- Having fully described my invention what I claim as new and desire to secure by Letters-Patent is:
1. In a vehicle, the combination with a frame, front and rear axles and wheels, of ratchet wheels secured to the rear axle, sprocket members mounted on said rear axle, dogs carried by said members and cooperable with said ratchet wheels; a connected series of links pivotally connected at one end with the lower portion of each ratchet member, and means connected with the upper portions of the connected series of links for manually operating said links to turn said sprocket members.
  2. In a vehicle, the combination with a frame, front and rear axles and wheels, of a ratchet wheel secured to the rear axle, a sprocket member loosely mounted on said rear axle, a pivoted dog carried by said sprocket member, a sprocket chain connected at one end with the lower portion of said sprocket member, and means connected with the upper end of said sprocket chain for imparting motion in one direction to said sprocket member.
  3. In a vehicle, the combination with a frame, front and rear axles and wheels, of a ratchet wheel secured to the rear axle, a sprocket member loosely mounted on said rear axle, a pivoted dog carried by said sprocket member, a sprocket chain connected at one end with the lower portion of said sprocket member, means connected with the upper end of said sprocket chain for imparting motion in one direction to said sprocket member, and a spring for moving said sprocket member in the opposite direction.
  4. In a vehicle, the combination with a frame, a rear axle and wheels, of ratchet wheels secured to the rear axle, plates loosely mounted on said axle and provided with laterally projecting lugs forming sprocket teeth, a spring actuated dog carried by each plate and cooperable with the adjacent ratchet wheel on the axle, sprocket chains connected at their lower ends with the lower portions of the respective plates, rods or pitmen connected with the upper ends of the respective chains, and means for manually operating said rods or pitmen.
5. In a vehicle, the combination with a frame, a rear axle and wheels, of ratchet wheels secured to the rear axle, plates loosely mounted on said axle and provided with laterally projecting lugs forming sprocket teeth, a spring actuated dog carried by each plate and cooperable with the adjacent ratchet wheel on the axle, sprocket chains connected at their lower ends with the lower portions of the respective plates, rods or pitmen connected with the upper ends of the respective chains, and means for manually operating said rods or pitmen.
6. In a vehicle, the combination with a frame, a rear axle and wheels, of a ratchet wheel secured to the rear axle, a plate hung on the rear axle, a spring actuated dog carried by said plate and cooperable with said ratchet wheel, means for swinging said plate a crank-shaft, supporting means therefor, and a hand lever connected with said crank-shaft for operating the latter to move said dog out of cooperative relation with the ratchet wheel.
7. In a vehicle, the combination with a frame, a rear axle, springs between the rear axle, and frame and ground wheels, of ratchet wheels secured to the rear axle, plates hung on the rear axle, dogs carried by said plates and cooperable with the ratchet wheels, manually operable means for swinging said plates in one direction, springs for moving said plates in the reverse direction, one end of each of said springs being connected with one of said plates, and means constituting anchors for the other ends of said springs.
8. In a vehicle, the combination with a frame, a rear axle, and wheels, of springs between the rear axle and frame, a ratchet wheel secured to the rear axle, a plate hung on the axle, a spring actuated dog carried by said plate and cooperable with the ratchet wheel, a yoke member between the first mentioned springs, a spring encircling the axle and connected at one end to said plate and at the other end with said yoke member, manually operable means for actuating said plate in one direction, a crank-shaft mounted in said yoke member, and manually operable means for moving said crank-shaft to move said dog out of cooperative relation with the ratchet wheel.
- In testimony whereof, I have signed this specification.

AXEL W. HAWKINSON.
